ABSTRACT OF THE DISCLOSURE

A higher mechanical force over uniform distance in response to mechanical pressures or electric pulses of varying amplitude over varying duration is provided for one or a multiple of devices to be shifted by a simple, compact, inexpensive high gain power transmission system. An electric motor driven power roll has one or more flexible bands arranged loosely about the periphery. One end of each band is coupled to an operating lever, preferably in the form of a hanger compactly encircling the power roll and the band on one side. The hanger is pivoted on one side of the roll and connected to one end of the band on the other side of the roll. The device to be shifted is attached to an extension of the hanger near the pivot. The band is connected to the lever on the other side of the roll beyond which extends a disengaging portion of the lever. A pressure roller is arranged on an arm to press the band into engagement with the peripheral surface of the roll. An armature is arranged for movement in response to manual pressure on a key or electric energization of a magnet, or the like. The movement of the armature is exerted through a mechanical latch to cause the arm carrying the pressure roller to press the band into frictional contact with the moving power roll. The band then pulls the lever in a direction for shifting the device as desired and opening the mechanical latch through action of the disengaging extension of the lever. Thus uniform travel of the device to be shifted obtains from applied force which is not necessarily uniform as to time or amplitude or distance traveled.

This application is related to co-pending U.S. patent applications Ser. No. 829,653 filed on the 2nd day of June 1969, of Paul Anthony Gilovich, Reynold Benjamin Johnson, Edward Everett Long, David Harwood McMurtry, Ernest George Nassimbene, Thomas Frank O'Rourke and George Edmund Price for Mechanical Type Printing Apparatus, Ser. No. 829,652 filed on the same day, of Reynold Benjamin Johnson, Edward Everett Long and George Edmund Price for a Key Responding Selector Mechanism.

The invention relates to an actuator mechanism for accurately shifting a mechanical device, and it particularly pertains to such mechanisms for mechanical type printing apparatus but it is not limited thereto.

In the contemporary alphanumeric character printing art, attention is being directed to simplified, low cost, manually operated type printing apparatus for use in conjunction with data processing systems such as commercial billing systems, and the like, and Computer Assisted Instructional systems. Such apparatus is in need of low cost but accurately controllable electric power driving mechanisms.

Conventional wire printing apparatus, printing telegraph apparatus, and various forms of typewriting apparatus have used electric motor driven power rolls and linkages of expensive construction and critical dimensions

for this purpose. Examples of this prior art are to be found in the following U.S. patents:

2,851,141, September 1958, Kistner, 197—1; 2,954,108, September 1960, Lenney, 192—81; 3,354,995, November 5, 1967, Morris, 192—3.5; 3,386,650, June 1968, Hildebrandt et al., 234—123; 3,404,616, October 1968, Koeber, 95—45.

According to the invention, the objects indirectly related hereinbefore and those which will appear hereinafter are attained in the mechanical power transmission system having a motor driven power roll, an operating lever, a flexible band having one end attached to the operating lever and loosely arranged about the periphery of the power roll, a pressure roller carried by an arm arranged to move the pressure roller toward the power roll for frictional engagement of the flexible band against the moving power roll thereby exerting a force on the operating lever to move it about the pivot point. The device to be shifted is coupled by conventional means to a point on the operating lever moving in the desired direction for the desired distance. The means for moving the pressure roller arm is coupled thereto by a disengageable latch normally engaged in readiness for operation. The latch is arranged to be disengaged by the operating lever as it is rotated by the power roll and flexible band at the point where the operating lever has reached the desired displacement for shifting the device to be actuated. An electrically energized magnet, a manually operated key, or the like, is arranged to move the armature latched to the pressure roller arm. Thus, uniform travel of the device to be shifted obtains from applied force which is not necessarily uniform as to duration applied or amplitude of force or distance traveled by the armature.

In order that the advantages of the invention may be readily attained in practice, a description of the preferred embodiment of the invention is given hereinafter, by way of example only, with reference to the accompanying drawing, forming a part of the specification and in which:

FIG. 1 is an isometric view of a power roll and actuator assembly according to the invention;

FIG. 2 illustrates printing apparatus embodying the invention;

FIG. 3 is a schematic diagram of the mechanical power transmission system according to the invention; and

FIG. 4 is a detailed drawing of one embodiment according to the invention.

An assembly of a plurality of mechanical power transmitting levers and an electric motor driven power roll is shown in FIG. 1. A rigid framework 210 supports an electric motor 212 and a cylindrical steel power roll 214 having a smooth peripheral surface made by an inexpensive machine process. The shaft of the motor 212 and the power roll 214 are directly coupled; there are a large number of electric motor commercially available which are suitable for the purpose. A number (13 as shown of thin flexible bands 216 are loosely arranged about the periphery of the power roll 214 with one end of each connected to an individual operating lever 218, the uppermost portion only of which is seen here. A like number of device actuating levers 220, . . . 229, 22Y, 22Z, and 230 are arranged in the frame 210 to pivot about the lower ends through very short uniform arcs with uniform forces toward and away from the longitudinal axis of the power roll 214. This movement is brought about in this embodiment by means of individual lever coupling links 232. Individual to each band 216, is a pressure roller 234 arranged at the end of a pressure roller arm 236 (just visible in this showing) and a pressure roller arm electromagnet 238 all arranged in the framework 210. These components will be shown and described in greater detail hereinafter.

FIG. 2 shows an assembly closely similar to the one above described inserted into printing apparatus of the type shown and described in the co-pending U.S. patent application, Ser. No. 829,653 for shifting a plurality of actuator plates of which only a spacing actuator plate 58 and four character segment selecting plates 60-63 are shown in the interests of clarity. The spacing plate actuating lever 230 extends through apertures in the plates of such dimensions that the spacing selector plate 58 only is moved forward by movement of the spacing plate actuator 230, either in response to electric energy applied to the pressure roller arm energized electromagnet 238, or the manipulation of the escapement release and carrier return lever 134 bearing on the upper end of the actuating lever 230. The spacing selector plate 58 is also moved each time the space bar 100, or any of the keys 70 are depressed, either to space manually or to space automatically after the selection of a character segment. Others of the levers 220-22Z will each actuate one character segment selecting plate and the spacing plate 58. There are instances in which all thirteen device actuating levers and all plates are moved and there are other instances when one out of eleven of the character segment selected plate device actuating levers are moved which also carries the spacing plate 58 forward at the same time. In this view, the operating lever 218 is seen to be in the configuration of a hanger encircling the power roll 214 and the flexible band 216 on one side rendering a very compact overall structure. The operating hanger lever 218 rotates about a fixed pivot 240 in the clockwise direction when the pressure roller 234 presses the flexible band 216 against the clockwise rotating power roll 214. In this illustration, the pressure roller arm 236 is made of resilient member welded to the armature 244 of an electromagnet 238 in the configuration of an inexpensive relay. In this arrangement, the flexible band 216 is permitted to slip at the end of the stroke of the device actuating lever 230 due to the resilience of the springy pressure roller arm 236. This springy arm release is satisfactory for many applications, however, a completely releasable latch mechanism will be described hereinafter.

FIG. 3 is a schematic diagram illustrating the essentials of the mechanical power transmission system according to the invention. The operating lever 218' pivots counterclockwise about the pivot point 240' by tension of the flexible band 216' exerted at the moving pivot point 242'. This movement is in response to the energizing of an electromagnet 238' attracting an armature 244' rotatable clockwise about a pivot point 246'. A manual push button 248 might alternately be used to rotate the armature 244'. The rotation of the armature member 244' rotates the pressure roller arm 236' through the intermediary of a latch mechanism shown here as a first element 251 depending from the pressure roller arm 236' at a moving pivot 254' and a second element 252 having one end connected to the first element 251 at a moving pivot 256 and at the other end to a point on the operating lever 218' at a moving pivot 258. In operation, a shoulder portion 260 of the armature 244' urges the first element 251 upward to bring the pressure roller 234' into engagement with the flexible band 216' and the power roll 214'. This action rotates the operating lever 218' counterclockwise for moving devices at either or both moving pivots 262 and 264 as desired. When the operating lever 218' reaches the end of the predetermined rotation thereof, the first element 251 is urged off the shoulder 260 by the second element 252 so that continued energization of the magnet 238' (or continued pressure on the push button 248) will have no further control of the operating lever 218' and the device connected to it.

FIG. 4 illustrates a preferred embodiment of the mechanical power transmission system according to the invention. The driven power roll 214" continuously rotates in the clockwise direction. A flexible band of suit-

able material such as gasket paper material more commonly known by the registered trademark "Vellumoid®" or as polyethylene glycol terphthalate, more commonly known by the registered trademark "Mylar®," is arranged loosely between the power roll 214" and the pressure roller 234". The end of the flexible band 216" is connected to the operating hanger lever 218" at the moving pivot point 242". When the pressure roller 234" engages the flexible band 216" with the power roll 214", the hanger lever 218" rotates about the fixed pivot 240". A connecting rod 232" is arranged in an extension portion 260" of the hanger 218" for substantially linear translation to the right. This draws a device actuating lever 220" through a short clockwise arc about the fixed pivot 262". The armature 244" rotates counterclockwise about a fixed pivot 246". In this embodiment, the pressure roller arm 236" also rotates about the fixed pivot 246". A moving pivot 254" is located on the pressure roller arm 236" remote from the pressure roller 234". Also rotatable about the moving pivot 254" is a latch member having two portions 251" and 252". The first part 251" engages a pawl 260" portion of the armature 244". When the armature 244" is attracted counterclockwise by the electromagnet 238", portions 260" and 251" coact to rotate the pressure roller arm 236" counterclockwise urging the pressure roller 234" into pressure translating relationship with the flexible band 216" and the power roll 214". When the operating hanger lever 218" has rotated the predetermined distance, a disengaging pin 258 strikes the portion 252" of the latching arrangement causing it to rotate counterclockwise and disengaging the pawl member 251" from the pawl member 260" on the armature 244" thereby releasing the pressure roller arm 236" and the pressure roller 234" from active relationship with the flexible band 216" and the power roll 214". With this arrangement, extension 260" exerts force over a uniform distance on the device actuating lever 220" despite any nonuniform amplitude or duration of the electric pulse applied to the electromagnet 238".

While the invention has been shown and described particularly with reference to a preferred embodiment thereof, and various alternative structures have been suggested, it should be clearly understood that those skilled in the art may effect further changes without departing from the spirit and scope of the invention.

The invention claimed is:

1. A mechanical power transmission system, comprising:
a continuously rotating drum,
a flexible band arranged loosely about said drum with one end coupled to an end of
a lever pivoted at a point beyond said flexible band,
a device to be powered coupled to the other end of said lever, and
a pressure roller arranged for pressing said free end of said flexible band onto said rotating drum, thereby to actuate said lever and power said device.
2. A mechanical power transmission system as defined in claim 1 and incorporating
an armature coupled to said pressure roller by a pawl and latch arrangement for releasably engaging the two,
an electromagnet for attracting said armature, and
a pin arranged on said lever to engage said pawl and disengage said armature when said lever has traveled through the useful range.
3. A mechanical power transmission system, comprising:
a continuously rotating drum,
a flexible band arranged loosely about said drum with one end coupled to an end of
a lever pivoted at a point beyond said flexible band and having the configuration of a hanger arranged about said rotating drum for actuation by said band

in a direction substantially tangentially of said drum, the pivot of said lever, the point of attachment of said one end of said band to said lever and the longitudinal axis of said rotating drum being substantially co-linear,

5 a device to be powered coupled to the other end of said lever, and

a mechanism for pressing said flexible band onto said rotating drum,

thereby to actuate said lever and power said device.

10 4. A ganged mechanical power transmission system comprising,

a continuously rotating elongated drum,

a plurality of flexible bands arranged loosely about said drum and side-by-side,

a plurality of hangers arranged about said drum and overlying said bands,

said hangers being pivoted at points beyond said bands and on a line parallel to the longitudinal axis of said drum,

said bands having one end of each attached to the overlying hangers at points on a line parallel to said axis and the first said line,

power takeoff links pivoted on said hangers above said hanger pivot points,

a plurality of elongated arms having pivots arranged in a line parallel to said axis and arranged on the side of said drum opposite said hangers,

a plurality of pressure rollers arranged on said arms, a plurality of pawls arranged on said arm,

a plurality of armatures pivoted concentrically with said pivots of said arms and having latches co-operating with said pawls, and

a plurality of electromagnets arranged for attracting said armatures

for pressing said pressure rollers and said bands against said drum

thereby to actuate said hangers.
